UNITED STATES PATENT OFFICE.

JOHN BARKER, OF LAWRENCE, MASSACHUSETTS.

GUIDE-BOARD FOR SPINNING-FRAMES.

SPECIFICATION forming part of Letters Patent No. 325,307, dated September 1, 1885.

Application filed January 2, 1885. (No model.)

To all whom it may concern:

- Be it known that I, JOHN BARKER, of Lawrence, county of Essex, State of Massachusetts, have invented an Improvement in 5 Guide-Boards for Spinning-Frames, of which the following description, in connection with the accompanying drawings, is a specification, like letters on the drawings representing like parts.
- 10 This invention has for its object to improve the construction of guide-boards, whereby they are made more durable, and whereby the friction on the yarn is reduced to the minimum.
- 15 Guide-boards as now commonly used are provided with eyelets, some of which are slotted and made of bone or porcelain inserted in holes made through the boards vertically, the eyelets being held in place by cement.
- 20 In accordance with my invention the guide-board slotted at its edge inward for the entrance of the yarn being spun is provided with pockets or recesses cut into the same from its top side to receive small cylinders 25 of glass or equivalent vitreous material, and the upper side of the said board, instead of being left exposed, as previously, being protected by a steel or metal plate, also slotted inward from one edge to correspond with the 30 slots in the guide-board, the said metal plate serving the purpose of not only holding the glass wearing-surfaces in place, but also covering and protecting the top of the guide-board, the slotted plate preventing wear or 35 injury to the board in the said slots either by wear or by blows.
- Figure 1 represents a sufficient portion of a spinning-frame to show the position of the guide-board with relation to the spindles and 40 rolls. Fig. 2, on a larger scale, represents a guide-board provided with my invention, the metal covering-plate being broken out opposite one of the slots to represent the glass cylinder, which is used as the wearing surface 45 or support for the yarn. Fig. 3 is a section of Fig. 2 in the dotted line x x .
- The frame-work A, bolster-rail B, lifting-rail C, the spindle D, flier E, spool F, roller-stand G, rolls H and I, and rail L are all in 50 common spinning-frames, so need not be here-
- in described. I have shown such old and common devices in order to illustrate the position of the hinged guide-board a , which it is the object of this invention to improve.
- The guide-board a is slotted at its front 55 edge, as at b , and is bored through, as at b' , to constitute a slit and eye for the reception of the yarn c which is being spun. The upper side of the guide-board is provided with a recess, d , which intersects the eye b' , and in 60 this recess is placed the cylindrical piece e , of glass or other vitreous material, that portion of the surface of the piece of glass referred to which intersects and crosses the line of b' serving as a rest or support against which 65 the yarn bears and over which it is drawn as it is spun and wound up in the usual manner. The upper side of the guide-board is provided with a steel or hard-metal plate, f , connected therewith by screws f' , and the said 70 metal plate is slotted from its front side inward, as at g , is rounded, as at g' , and at the inner end of said slot I have provided an eye, g'' , the inner rear wall of which in the dotted line x is located back of a vertical line 75 drawn to intersect the front edge of the glass support or guide e .
- The guide or support e is so located with relation to the upper end of the spindle and the rolls H I that the yarn is kept from contact with the metal plate f at the inner end of the notch therein, thus preventing the same from cutting or fraying the yarn.
- The metal plate f protects the wooden part 80 of the guide-board, which is slotted for the reception of the yarn, and any roughness of the board is not felt by the yarn, nor is the board in the slots liable to be injured or roughened by blows, as when not protected by the plate. The plate f also acts to retain 85 in place and cover the support or guide e .
- Instead of the flier E, I may use an ordinary cap without departing from my invention.
- I claim—
1. The guide-board slotted at b b' and recessed longitudinally at d , combined with the cylindrical supports or guides e , of vitreous material, placed in the said recesses, substantially as described.

95

100

2. The guide-board slotted at $b b'$ and recessed at d , and the vitreous supports or rests e , laid in the said recesses and crossing the rear edge of the opening b' , combined with 5 the metal top plate, f , slotted, as shown and described, and shaped to cover the guide-board and retain the supports or rests in place, all substantially as set forth.

In testimony whereof I have signed my name to this specification in the presence of two sub-
scribing witnesses.

JOHN BARKER.
